UNITED STATES PATENT OFFICE.

JAMES WARREN HALSTEAD, OF NORFOLK, VIRGINIA, ASSIGNOR TO FARMERS MANUFACTURING COMPANY, OF NORFOLK, VIRGINIA, A CORPORATION OF VIRGINIA.

BERRY BOX.

Application filed January 6, 1927. Serial No. 159,424.

This invention has relation to the class or type of fruit and vegetable baskets which have heretofore been made entirely of wood veneer. It has been customary to make these 5 boxes of two sheets of veneer crossed upon each other and bent up at their ends and bound together at their top edges by inside and outside wood strips. One very important advantage of this type of box is its rigidity. One very important disadvantage is 10 that the inside blank, at the four corners where it is bent to form the wings, splits vertically both during manufacture and while in use. One object of the present invention is 15 to so construct the box that its rigidity is preserved to a sufficient degree for practical purposes, while at the same time the aforesaid splitting of the sheet at the upright corners of the box is done away with, as more 20 fully hereinafter set forth.

In the drawing—

Fig. 1 is a perspective view; and

Fig. 2 is a transverse sectional view of a 25 box made in accordance with my invention; Fig. 3 is a plan view of the paper blank.

Two blanks numbered 5 and 6 respectively are the same shape, as usual, the blank 5 being a plain sheet without wings, while the blank 6 is provided with laterally-projecting 30 wings 7 at its ends. These two blanks are laid upon each other in crossed relation and their end portions are folded up to form the four side walls of the box or basket. They are fastened together where they cross each 35 other by a staple 8 or otherwise. The upper edges of the folded blanks are bound between stapled wood rim-strips 9, as usual. The flaps 7 lie as usual against the inner faces of the walls formed by the blank 5.

40 In the present invention, the blank 5 is made of wood veneer, as usual, but the blank 6, instead of being made of veneer wood, is cut from a paper sheet. Any suitable paper may be used; I prefer Kraft paper which is substantially waterproof or non-absorbent. This paper is very tough and strong and will 45 fold readily without cracking or splitting, while at the same time it will not be readily

affected by the moisture from the fruit or vegetables and will, therefore, maintain its 50 original shape for a sufficiently long time for practical purposes. Inasmuch as the paper blank has not the flexural strength that the wood blank has, it is preferable that the inner blank shall be the paper blank, as in that 55 way the wood blank will serve to support and brace the paper blank, thus enabling me to use comparatively thin inexpensive paper.

It is obvious also that, by thus using thin 60 paper for the larger, inner blank, there is a reduction in weight and consequently a saving in freight, a matter of great importance in articles of this sort. Also, the use of substantially non-absorbent paper for the 65 larger part of the inner surface of the box increases cleanliness and sanitarness. I also eliminate the waste caused by wooden blanks breaking, especially at the upright corners of the box where the wings 7 are bent at right-angles to form the closed corners and 70 lie against the adjacent side walls. Another advantage is that, in addition to avoiding splitting at the corners, an absolutely tight corner is provided, an entirely new thing in this type of basket. Thus closing the 75 corners makes the box an ideal shipping-package for small berries, such as huckleberries.

What I claim as new is:

1. A box or basket of the type set forth 80 consisting of crossed blanks folded to form a box and retained in shape by a rim, one blank being wood veneer and the other blank being bendable non-splitting paper which is bent to form upright closed corners and wings to engage with the adjacent sides.

2. A box or basket of the type set forth 85 consisting of crossed blanks folded to form a box and retained in shape by a rim, one blank being wood veneer and the other blank being bendable non-splitting paper which is bent to form upright closed corners and wings to engage with the inner surfaces of the adjacent sides.

In testimony whereof I hereunto affix my signature.

JAMES WARREN HALSTEAD.
